UNITED STATES PATENT OFFICE.

WILLIAM E. FICKLEN, OF NEW YORK, N. Y.

PROTECTING DEVICE FOR CURBS AND THE LIKE.

1,202,172.

Specification of Letters Patent. Patented Oct. 24, 1916.

Application filed June 7, 1912, Serial No. 702,233. Renewed September 12, 1913. Serial No. 769,544.

To all whom it may concern:

Be it known that I, WILLIAM E. FICKLEN, a citizen of the United States, residing at New York city, county of New York, and 5 State of New York, have invented certain new and useful Improvements in Protecting Devices for Curbs and the like, of which the following is a specification.

My invention relates to improvements in 10 protecting devices or nosings for curbs, gutters, crossing blocks, expansion joints in concrete roadways, and the like.

An object of the present invention is to provide a nosing or protector, for the purposes stated, of such construction as to be anchored at unusual depth in the concrete or artificial conglomerate, forming the curb or block, and in which the anchoring means is integral with the rest of the structure, so 15 as to remain connected therewith, no matter to what blows or stresses the nosing is subjected under traffic.

Another object of the invention is to have the protector of such design as to be capable 20 of cheap construction, and also to be of such design as to be readily and accurately set into the unset concrete or other mastic.

A further object of the invention is to provide a nosing or protector which, in 25 combination with the features above mentioned, may be constructed to present a tough, non-slipping surface to traffic.

Other features of the invention will appear upon reference to the accompanying 30 drawings, in which a short length of the protectors is shown in perspective.

Referring to the drawings, the two wings 35 of the protector or nosing are shown at 1 and 2. Ordinarily the protector is so positioned in the concrete that wing 1 lies flush with the top surface of the paving block or curb, and wing 2 flush with the vertical face of the block or curb. If the occasion demands, however, the protector may be so 40 positioned as to have one, only, of its wings flush with a surface of the block, the other wing in such instance being directed into the body of the block.

Cut and turned out of each of the wings 1 45 and 2, at intervals along the same, are tongues or lugs 3 and 4. Only one of each is shown in the short length of bar of the drawings, but it will be understood that in the long length of bar used in practice, 50 there will be many tongues on each wing.

To form the tongues, the wings are so cut that the tongues, before being turned out, extend lengthwise of the bar or protector. The tongues may thus be made of any desired length; and any depth of anchorage 55 may therefore be secured without necessitating any special attachments to the bar. The cuts are preferably made as near the outer edges of the wings as practicable so that the tongues stamped from one wing 60 may lie at some depth in the concrete below or behind the other wing. The tongues are also preferably shaped to have hooks 5 at their distal ends. Preferably also, particularly where great depth of anchorage is de- 65 sired, the tongues are turned to a position at right angles to the wing from which they are formed, and when so positioned, those on one wing are disposed at right angles to those on the other wing. No matter, there- 70 fore, whether the tendency is to lift the bar or to move it sidewise, there is always one set of tongues which lie practically cross- 75 wise to the direction of stress, at some distance from the surface toward which there 80 is a tendency to move the bar, and another set of tongues disposed more nearly in the line of the attempted movement, with such deep anchorage as effectively to assist the first set to resist displacement of the bar, 85 and to prevent cracking of the concrete along the plane of the first set. In resisting movements in directions oblique to the surfaces, both sets of tongues have in part the same functions; and this is likewise the 90 case when the bar is so struck or pressed upon as to tend to move it longitudinally. If the tongues are disposed at other than right angles to the wings from which they are formed, then both sets will always be in 95 part crosswise to any direction of attempted movement; but the same depth of anchorage from the surface will not be obtained unless the tongues are made longer.

In order to avoid slipping of horses, skidding, etc., the bar is so constructed that long continuous metallic surfaces will not be presented at the surface of the pavement when the bar is used for expansion joints or road crossings. The concrete which fills the 105 openings 6, formed in turning out the tongues, may serve more or less to break the continuity of the metallic surface and to provide a grip for traffic. Unless, however, the tongues are near together, it is ad- 110

- visible to supplement these concrete gripping points by others, which, as shown in the drawings, are formed at 7 by turning lips 8 out of the top wing 1. The openings 5 6 and 7 together provide a substantially continuous non-slipping surface at the top of the bar, by reason of the concrete which fills these openings. The lips 8 serve as 10 additional anchoring means, being particularly useful in resisting longitudinal displacements. The openings 6 and 7 are furthermore important in setting the bar into the concrete. The bar may be positioned in the concrete, either by forcing the bar into 15 the unset concrete, or by holding the bar stationary while the concrete is flooded against it and under its horizontal wing. It is extremely desirable to have the concrete finally in actual contact with the bar 20 at all points of the inner surface of the wings 1 and 2. The holes 6 and 7 permit the workman to see the level of the concrete below the horizontal wing 1, and thus to determine when the concrete properly engages the bar. If the bar and concrete be 25 forced together sufficiently, the concrete will ooze through the openings 6 and 7 and thus automatically indicate the correct setting of the bar.
- 30 The structure shown in the drawings is susceptible of various modifications within the scope of the invention, particularly in respect of the shape and disposition of the anchoring tongues, and surface openings.

What I claim is:

- 35 1. An edge protector consisting of a bar which is angle shaped in cross section, thereby comprising two longitudinal sections, said bar having anchor members cut from each section, said anchor members being bent 40 away from said sections, the anchor members of one section extending parallel to the surface of the other section.
2. An edge protector comprising a bar which is angle shaped in cross section, 45 whereby said bar is composed of two longitudinal sections, said sections each having anchor members cut therefrom along lines extending longitudinally of said bar, said members being bent away from said sections, 50 the members of one section extending parallel to the other section.
3. An edge protector comprising a bar which is angle shaped in cross section, 55 whereby said bar is composed of two longitudinal sections, said sections each having anchor members cut therefrom along lines extending longitudinally of said bar, said members being bent away from said sections, 60 the members of one section extending parallel to the other section, said members being hook shaped at their outer ends.

Signed by me at New York city, N. Y., this 31st day of May, 1912.

WILLIAM E. FICKLEN.
